UNITED STATES PATENT OFFICE

ERNEST BRISTOW LE MARE, OF ST. HELENS, ENGLAND, ASSIGNOR TO PILKINGTON BROTHERS LIMITED, OF LIVERPOOL, ENGLAND, A BRITISH REGISTERED COMPANY

PRODUCTION OF GLASS IN STRIP FORM AND APPARATUS THEREFOR

Application filed April 27, 1929, Serial No. 358,439, and in Great Britain May 1, 1928.

This invention relates to the production of glass in strip form and has for its object an improved apparatus whereby lengths of strip may be formed intermittently and the strips passed through a lehr at a speed equal to the speed of formation averaged over the periods of formation and intermittence.

In the production of glass in strip form, it is frequently necessary to form the strip at high speed, say, 30 feet per minute. If the strip were passed through a lehr at this speed, the necessary length of lehr would be impracticable.

It has been proposed to form strips at the desired high speed, but intermittently, the average speed of formation, including the time of intermittence, being a speed, say, 3 feet per minute, which is suitable for a lehr of normal length, and certain devices have been proposed whereby the strip is received at the high speed and reduced in speed to the low speed.

According to this invention the strip is received at the high speed and reduced in speed in a way which is simpler, maintains better the flatness of the strip and by simpler devices.

In the accompanying drawings:—

Figure 1 is a longitudinal section partly broken away, of a lehr with roller bed according to one form of the invention,

Figure 2 is a side view of a portion thereof on a larger scale showing the driving devices of the rollers, and

Figure 3 is part horizontal section through the line X—X of Figure 2, showing the said driving devices.

Referring to the drawings, the lehr 1 is provided with a bed of rollers 2. The rollers 2 are driven by means to be hereinafter described at different speeds, being divided, for purposes of driving, into groups indicated by the letters A, B, C and D in Figure 1. The rollers of the group A, being the rollers on which the strips of glass are received as they are formed, either directly from the forming apparatus or after passage over a platen or other form of bed, are driven at a peripheral speed equal to or slightly greater than the speed of formation of the strips. The rollers

of the second group B are driven at a lower speed, those of the group C at a still lower speed and those of the group D at a still lower speed. The remaining rollers of the lehr, hereinafter called the ordinary rollers, are 55 driven all at the same speed, which is lower than that of the rollers of the group D. Four groups of rollers are here described as preceding the ordinary rollers, but any convenient number of groups may precede them. 60 Further it will be assumed in this description that all the rollers are positively driven, but some of them may be idle rollers.

The shafts 3 of the rollers 2 turn in bearings 4 supported on a foundation wall 5 outside the lehr wall 6. On the portions of the shafts 3 extending beyond the bearings 4 of certain of the rollers, are mounted free-wheel clutches having an inner member 7 and an outer member 8. The outer covering plate 70 9 of one of these clutches is not shown in Figure 2, so as to allow these members to be seen. The free-wheel clutches 7, 8 may be of any type and need not be further described; their function is to enable the rollers 75 to be driven at a given speed while leaving the rollers free to turn at any higher speed.

The inner members 7 of the free-wheel clutches are fixed on the shafts 3 and chain wheels 10 are fixed on the outer members 8. 80 The chain wheels 10 of the rollers of any one group of rollers are driven by a chain 11 which engages the chain wheels on their upper portions and, below, passes over idle wheels 13 and a driving chain wheel 12, of 85 which the shaft is driven in any convenient way. In Figure 2 are shown some of the rollers of two adjacent groups, the right-hand group having a driving chain wheel similar to the wheel 12 of the left-hand group and the left hand group having idle wheels similar to the wheels 13 of the right hand group. 90

For the purpose of describing the operation of the lehr, the following assumptions in regard to speeds, lengths and time will 95 be made, namely, it will be assumed that strips of glass 30 feet long are produced at a speed of 30 feet per minute, with intervals of nine minutes between the completion of one strip and the start of the next strip; that 100

the group A of rollers is 15 feet long and the rollers turned at the peripheral speed of 30 feet per minute; that the group B, C and D of rollers are respectively 29, 25 and 20 feet 5 long and the rollers driven through free-wheel clutches at the speeds of 27, 22 and 14 feet per minute respectively; that the ordinary rollers are driven at the speed of 3 feet per minute and are driven through free-wheel clutches over a length of 30 feet. 10

The strip of glass 14 is received by the group A of rollers, which are driven at the speed of formation of the strip. When half the strip has passed on to the rollers of group A, 15 its forward edge passes on to the rollers of the group B, which are driven through free-wheel clutches and, therefore, offer no appreciable resistance to the passage of the strip at a speed slightly higher than that at which 20 they are driven. When however, the back edge of the strip approaches the end of the group of rollers A, the strip is then being driven at 30 feet per minute by only a few rollers, while the greater portion of it is 25 resting on the rollers of group B; then the resistance offered by the large number of these rollers becomes appreciable, and there is some slip between the strip and the rollers of group A, which gradually increases as 30 the number of rollers of group A driving the strip diminishes. Thus the speed of the strip is gradually reduced from 30 feet per minute, namely the speed of the rollers of group A to 27 feet per minute, the speed of 35 the rollers of group B.

Similarly, the strip passes from the rollers of group B on to those of group C, its speed is gradually reduced from 27 feet per minute to 22 feet per minute and, again, as it passes 40 on to the rollers of group D its speed is gradually reduced to 14 feet per minute and, finally, as it passes on to the ordinary rollers, its speed is gradually reduced to 3 feet per minute, at which speed it passes through the 45 rest of the lehr.

In this way the speed of the strip from its formation to its passage on to the ordinary rollers is gradually reduced from 30 feet per minute to 3 feet per minute, without at 50 any time exercising any retarding force likely to injure the strip and without allowing the strip to rest on a bed of rollers turning at too low a speed having regard to the temperature of the strip.

55 The next strip, formed after an interval of nine minutes, gradually approaches the strip previously formed, and reaches the latter when it has passed on to the ordinary rollers, so that, on the ordinary rollers, which 60 constitute the greater portion of the lehr, the strips follow one another closely, and the lehr therefore is fully utilized.

The values of speed, length and time assumed above are taken only by way of example; the actual values are determined for

any given set of conditions so that the strip may be brought from the high speed to the low speed in the minimum time possible without causing deformation of the strip. Thus, for a period after its formation, the strip is 70 at a high temperature and soft, and consequently the difference in speed between the first and second groups of rollers must be small; as the strip becomes harder and harder, so the difference in speed between the following groups of rollers may be increased without causing injury to the strip. 75

The interval between the formation of one strip and the next can be so related to the time taken by a strip to reach the ordinary rollers 80 that the strips, when on the ordinary rollers, follow each other as closely as may be desired.

The means shown for driving the rollers by chains is by way of example only; they may be driven by any suitable devices, such as 85 bevel or spiral gears.

Having described my invention, I declare that what I claim and desire to secure by Letters Patent is:—

90 Roller-bed for intermittently receiving hot glass strips at a high speed and reducing their speed, comprising a first group of rollers, a single driving means therefor adapted to drive the rollers continuously at a constant speed corresponding to the speed of formation of the strip, a second group of rollers, a single driving means therefor tending to drive the rollers thereof at a constant low speed and a free-wheel clutch between the latter driving means and each one of at least a 95 portion of the rollers of the second group, adapted to permit each of the said rollers to turn freely at a higher speed than its driven speed. 100

In witness whereof I have affixed my signature hereto.

ERNEST BRISTOW LE MARE.
